UNITED STATES PATENT OFFICE.

JOHN F. COURSON, OF PITCAIRN, PENNSYLVANIA.

DRAFT-GEAR.

1,123,853.

Specification of Letters Patent.

Patented Jan. 5, 1915.

Application filed May 29, 1913. Serial No. 770,564.

To all whom it may concern:

Be it known that I, JOHN F. COURSON, a citizen of the United States, residing at Pitcairn, in the county of Allegheny and State of Pennsylvania, have invented certain new and useful Improvements in Draft Gears, of which the following is a specification.

My invention consists of an improvement in draft gears for railway cars, etc., and has for its object to provide a gear of simple construction and high efficiency, designed to utilize the resisting power of springs and the wedge releasing qualities of wedge blocks co-acting with housings or casings therefor, arranged between a central buffering member and the rear portion of a surrounding frame or casing, arranged and adapted to effect lateral compression of the spring members upon longitudinal movement of the friction-creating member co-acting with the friction producing spring housings.

The invention, as shown, also discloses the use of a novel construction of expanding friction-creating wedge blocks and a co-acting separating wedge having front and rear wedge members, which, however, is not necessarily a part of the present invention, but is shown as associated therewith, and which forms the subject matter of a separate application, to be hereafter filed.

The invention, as disclosed, also embodies the mounting of the apparatus in the car framing and the several parts necessary for its installation and operation with the car structure.

The particular object of the present invention is to provide, in a gear of this type, means for exerting resisting spring pressure and frictional resistance between the co-acting friction members, the construction preferably utilizing a plurality of spring and friction units, for successive operation, in combination with a relatively movable wedge member. These objects are accomplished, in one preferred form of the apparatus, hereinafter described, as illustrated in the accompanying drawings, in which—

Figure 1 is a central horizontal sectional view of the complete apparatus, in normal position, indicated by the section line I. I. of Fig. 2, the spring housings being shown in elevation, and illustrating the relative position of the friction member, partly broken away. Fig. 2 is a longitudinal ver-

tical sectional view, indicated by the line II. II. of Fig. 1. Fig. 3 is a cross sectional view, indicated by the line III. III. of Fig. 2. Fig. 4 is a cross sectional view, indicated by the line IV. IV. of Fig. 2. Fig. 5 is a detail sectional view showing a modified construction of the front wedge-actuated friction members. Fig. 6 is a perspective detail view of the front expanding wedge. Fig. 7 is a similar view of one of the friction shoes actuated thereby. Fig. 8 is a view similar to Fig. 1, showing the gear under compression. Figs. 9 and 10 are perspective detail views of the casing, on a reduced scale. Fig. 11 is a perspective detail view of the wedge member for the spring housings. Figs. 12 and 13 are similar views of the front and rear spring housings respectively.

In the drawings, 2 represents the drawbar of a coupler fixedly connected with the yoke 3 by transverse bolts 4 in the manner customary in this art, said yoke embracing the casing 5, at top and bottom, as shown, the yoke and casing being located between the central sills 6, 6. A bearing block or piece 7 is set against the rear end of casing 5, and its closing end wall, hereinafter described, against the outer end of which block bears the rounded end 8 of yoke 3 with an interposed filling block 9, preferably secured to the end of the yoke. The front stops 10 extend inwardly from each side of the center sill 6 which sustain the pulling effect of the draft gear and impart it to said sills, while similar rear stops 10' act to receive and impart buffering strains in the same manner.

The casing 5 is generally rectangular in cross section, and is mounted between the sills 6, supported upon any suitable cross member 11 between the sills, having suitable clearance for the yoke 3. When the casing is intended to be used in connection with the supplemental front expanding wedges, its front end portion 12 may be made cylindrical, as shown, with inner cylindrical friction faces 13 adapted to receive the several friction shoes 14 and to co-act therewith as they are expanded by the central buffering wedge B. Said wedge abuts by its forward end against a follower 15 normally engaging the front stops 10 and rear end of the drawbar 2, wedge B having two sets of wedge faces, b and b',

respectively, adapted to engage the wedge faces c and c' respectively of each friction-creating shoe 14. The wedge faces thereof are disposed inwardly and backwardly at the front and rear portions of the friction shoes, whereby to effect even distribution of the pressure throughout the shoes, and by them against the interior annular surface 13 of the cylindrical extension 12 of case 5.

At its rear portion, casing 5 is open and provided with a closing gate or wall 16 having edge portions extending inwardly at each side into receiving slots or cavities 16' in the rear side portions of the casing, or mounted in any other suitable manner, the door thus closing the interior and providing by its inner face a backing for the rear spring housing. It will be obvious, also, that any other suitable construction of casing may be adopted.

The spring housings, where two are used, are indicated by the numerals 17, 18, each inclosing a coiled spring 19 of well-known construction, bearing by one end against the inner end of the housing, and by its other end against the opposite side wall of the casing 5, the housings and springs being in alternating positions, as shown. The front spring housing 17 is provided at top and bottom with laterally extending wedge abutments 20 having wedge faces 21 of sufficiently blunt angle to insure release, beyond which are wedge faces 22, much more acute, and adapted to exert greatly increased pressure by the action of the co-acting acute wedge faces of the actuating wedge A. The rear spring casing 18 is provided at opposite sides with similar wedge abutments 23 having wedge faces 24, also sufficiently blunt to insure free release.

The wedge member A, as shown, is in the form of a bifurcated or double-sided frame having a central forwardly extending portion a adapted to receive the force of impact from the drawbar in buffing or to transmit pulling strains thereto. Each side member a' , a'' of the wedge member A extends backwardly, above and below the spring housings 17, 18, respectively, in engagement with inwardly extending longitudinal strips or guiding rib abutments 25 of casing 5. By this means the wedge member is maintained in central alignment and is not deflected by its wedging engagement with the spring housings.

The wedge member A is provided at the inner sides of its side arm members a' with blunt angle wedge faces a^2 adapted to engage the faces 21 of spring housing 17, and similar faces a^3 beyond faces a^2 adapted to engage wedge faces 24 of spring housing 18. As shown, these wedge faces, and the wedge faces of the respective spring housings, are opposed to each other in direction, so that as the wedge member A travels longitudi-

nally across the sides of the housings in buffing, or the housings are moved inwardly between the sides of the wedge member in pulling, the action of faces a^2 , a^3 , on faces 21 and 24 is to force the housings laterally in opposite directions, compressing the springs therein by the back walls of the housings, against the opposing faces of the sides of casing 5. Forwardly beyond wedge faces a^2 are acute angle wedge faces a^4 , forming continuations of blunt angle faces a^2 , and operable to engage the acute angle wedge faces 22 of the first spring housing, and to bind thereagainst with powerful force and resulting friction.

It will be observed from Fig. 1 that the initial engagement of wedge faces a^2 with faces 21 of the first housing 17 will operate to thrust the housing laterally to a considerable extent before wedge faces a^3 engage faces 24 of the next adjacent housing 18, sufficient clearance space being provided to allow of the initial travel and action on the first housing, sufficient to substantially compress the first spring 19 to the full extent of its movement, so that when the second housing is engaged and thrust laterally, its resistance will be in addition or supplemental to that of the first housing and spring, thereby accumulating the frictional and spring resistance. Just after wedge faces a^3 commence to engage faces 24 of the rear housing, the acute angle faces a^4 of the wedge member A also engage corresponding faces 22 of the first housing 17, binding 100 thereagainst with intensified pressure, almost completely closing the spring, and effecting additional resisting friction. This insures the releasing of wedge faces a^4 and 22 by the last portion of the return expansion of the spring of the rear housing. As shown, the adjacent sides of the housings will be forced into tight contact with each other, and the opposite back wall of the rear housing will also be forced into tight 110 contact with the rear wall 15 of the casing, so that as the housings are forced laterally in opposite directions, they generate a high degree of friction between them and the rear one against the end of the casing. By these 115 means the friction resistance is greatly multiplied and is developed in proportion to the pressure generated by either pulling or buffing shocks. Upon release of pressure, the wedge member A will be thrust forwardly 120 by the expanding action of spring 19 of rear housing 18 and blunt angle wedge faces 24— a^3 , effecting positive forward movement of the wedge member, entirely releasing acute angle faces 22— a^4 , the releasing being 125 completed by blunt angles 21— a^2 , thus collapsing the gear, and effecting resumption of the normal position of the several parts. When combined with the friction shoes 14 and wedge B between the forward end of the 130

friction member A and drawbar 2, the spreading action of the friction shoes 14 is effected directly through the engagement of wedge faces *b* and *b'* with faces *c* and *c'*, release being effected in the same manner on separation of the parts, due to the blunt angle of the several co-acting wedges. The frictional resistance of shoes 14 will thus greatly supplement the resistance of the 10 spring and friction members above described, so that the gear as a whole is capable of developing a very high resistance to pressure, with prompt, free and invariable release.

15 While I have shown in the principal figures the wedge B as made in one piece, it will be understood that it may consist of two separate wedges B' and B'', with an intervening spring *b*², as clearly shown in Fig. 5, 20 the construction of the shoes 14' and of the other co-acting parts being as already described. The advantage of this construction is that the equalization of the bearing contact of the wedge members is insured, notwithstanding any variation in the location 25 or finishing of the wedge faces *c*², *c*³, of the several shoes.

The construction and operation of the gear will be readily understood from the 30 foregoing description. It is comparatively simple and compact, readily assembled or taken apart, or applied to the under-frame of a car structure, while being capable of generating an extremely high degree of resistance to and absorption of the several 35 shocks arising in the usual car service.

Having described my invention, what I claim is:

1. In a friction draft gear, the combination 40 with the supporting frame and the relatively movable drawbar, of a spring and a laterally movable housing therefor within the supporting frame provided with blunt and acute wedge faces, a longitudinally movable wedge member having corresponding faces for engagement thereof adapted to shift the housing laterally on inward movement, and additional means resisting inward movement of the wedge member, substantially as set forth.

2. In a friction draft gear, the combination 55 with the supporting frame and the relatively movable drawbar, of a plurality of oppositely acting movable wedge members in frictional engagement with each other, resisting springs therefor, and a longitudinally movable wedge member adapted to transmit drawbar strains to said wedge members successively transversely to the direction of said strains, substantially as set forth.

3. Resisting mechanism for a draft gear 60 of the class described consisting of a casing adapted to be mounted in a car frame provided with longitudinal guides, a wedge

member mounted in said guides, oppositely acting transversely movable wedge members engaging said wedge member and each other and resisting springs therefor, substantially as set forth.

70

4. Resisting mechanism for a draft gear of the class described consisting of a casing adapted to be mounted in a car frame for longitudinal movement therein and provided with interior longitudinal guides, spring 75 mechanism, a housing therefor having wedge portions, and a bifurcated wedge member mounted in said guides embracing the housing and adapted to transmit buffing or pulling strains to said housing transversely to 80 its line of movement, substantially as set forth.

5. In a friction draft gear, the combination with the drawbar and car frame, of a casing having longitudinal guides, means 85 closing the rear end of the casing, means connecting the casing with the drawbar, spring mechanism within the casing, a housing therefor having wedge portions on opposite sides, and a longitudinal bifurcated 90 wedge member having co-acting wedge portions operable to transmit buffing or pulling strains to said housing and from said housing to the casing and from the casing to the car frame, substantially as set forth.

95.

6. In a friction draft gear, the combination with the drawbar and car frame, of a casing having longitudinal guides, means closing the rear end of the casing and means connecting it with the drawbar, spring 100 mechanism within the casing, a housing therefor having wedge portions, a longitudinal wedge member having co-acting wedge portions operable to transmit buffing or pulling strains to said housing and from said 105 housing to the casing and from the casing to the car frame, and supplemental wedge mechanism interposed between the front end of the wedge member and the rear end of the drawbar, substantially as set forth.

110

7. In a friction draft gear, the combination with the drawbar and car frame, of a casing having longitudinal guides, means closing the rear end of the casing, means connecting the casing with the drawbar, a 115 plurality of resisting springs engaging opposite inner sides of the casing, housings therefor having oppositely disposed wedge portions, and a longitudinal wedge member slidably mounted between the guides of the casing having wedge faces adapted to successively engage the wedge portions of the housings and to move them transversely in opposite directions against the springs, substantially as set forth.

120

8. In a friction draft gear, the combination with the drawbar and car frame, of a casing having longitudinal guides, means closing the rear end of the casing, means connecting the casing with the drawbar, a 130

plurality of resisting springs engaging opposite inner sides of the casing, housings therefor having oppositely disposed wedge portions, and a longitudinal wedge member 5 slidably mounted between the guides of the casing having wedge faces adapted to successively engage the wedge portions of the housings and to move them transversely in opposite directions against the springs, and 10 to effect binding wedge engagement with the first of said housings at the end of its movement, substantially as set forth.

9. In a friction draft gear, the combination with the supporting frame and a relatively 15 movable drawbar, of a plurality of springs, each bearing by its end against the frame, oppositely acting housings therefor frictionally engaging each other, each having wedge faces, and a longitudinally movable 20 wedge member adapted to engage said housings and compress the springs successively against the frame.

10. In a friction draft gear, the combination with the supporting frame and a relatively 25 movable drawbar, of a plurality of springs, each bearing by its end against the frame, oppositely acting housings therefor frictionally engaging each other each having wedge faces, and a longitudinally movable 30 wedge member adapted to first engage one of said housings and compress its spring against the frame and while maintaining wedge action and compression on said housing and spring to then engage another of 35 said housings and compress its spring against the frame.

11. In a friction draft gear, the combination of a casing, a drawbar, means connecting the casing and drawbar, a spring, a laterally 40 movable housing therefor, a longitudinally movable wedge member adapted to shift the housing laterally to compress the spring, and supplemental wedge mechanism 45 interposed between the front end of the wedge member and the rear end of the drawbar.

12. In a friction draft gear, the combination of a casing, a drawbar, means connecting the casing and drawbar, springs engaging 50 opposite sides of the casing, housings therefor having oppositely disposed wedge portions and frictionally engaging each other, and a longitudinal wedge member having wedge faces adapted to engage the 55 wedge portions of the housings and move them in opposite directions against the springs.

13. In a friction draft gear, the combination of a casing, a drawbar, means connecting the casing and drawbar, a plurality of oppositely 60 acting spring housings having springs and wedge faces, and a longitudinally movable wedge member adapted to shift the first housing laterally and to then

shift the next adjacent housing in the opposite direction. 65

14. In a friction draft gear, the combination of a casing, a drawbar, means connecting the casing and drawbar, a plurality of oppositely acting spring housings having 70 springs and wedge faces, and a longitudinally movable wedge member adapted to shift the first housing laterally and to then shift the next adjacent housing in the opposite direction, and to continue to shift the 75 first housing to a lesser degree.

15. In a friction draft gear, the combination of a casing, a drawbar, means connecting the casing and drawbar, a plurality of oppositely acting spring housings having 80 springs and wedge faces, and a longitudinally movable wedge member adapted to shift the first housing laterally and to then shift the next adjacent housing in the opposite direction, and to maintain pressure on 85 the first housing.

16. In a friction draft gear, the combination of a casing, a drawbar, means connecting the casing and drawbar, a plurality of oppositely acting spring housings having 90 wedge faces and springs engaging the casing and a longitudinally movable wedge member adapted to force the first housing against the next adjacent one and to shift the first housing laterally in frictional engagement with said adjacent one. 95

17. In a friction draft gear, the combination of a casing, a drawbar, means connecting the casing and drawbar, a plurality of oppositely acting spring housings having 100 wedge faces and springs engaging the casing and a longitudinally movable wedge member adapted to force the first housing against the next adjacent one and to shift the housings laterally in opposite directions 105 and in frictional engagement with each other.

18. The combination with car framing, of a movable casing mounted therein, a drawbar connected with the casing, a spring and a laterally movable housing therefor both confined within the casing, and a longitudinally movable wedge member within the casing operable across the outside of the housing adapted to shift it laterally to compress 115 the spring. 110

19. The combination with car framing, of a movable casing mounted therein, a drawbar connected with the casing, a plurality of springs and laterally movable housings 120 therefor both confined within the casing, and a longitudinally movable wedge member within the casing operable across the outside of the housings adapted to shift them laterally in opposite directions to compress the springs. 125

20. In a friction draft gear, the combination of a movable casing, a drawbar con-

nected with the casing, a spring, a laterally
movable housing therefor within the casing
provided with wedge portions, and a longi-
tudinally movable wedge member within the
5 casing embracing the housing and adapted
to transmit buffing or pulling strains to said
housing transversely to its line of movement.

In testimony whereof I hereunto affix my
signature in the presence of two witnesses.
